UNITED STATES PATENT OFFICE.

GEORGE L. SCHOFIELD, OF KANSAS CITY, MISSOURI.

BALANCED ROTARY VALVE.

1,186,848.

Specification of Letters Patent. Patented June 13, 1916.

Application filed September 14, 1915. Serial No. 50,685.

To all whom it may concern:

Be it known that I, GEORGE L. SCHOFIELD, a citizen of the United States, residing at Kansas City, in the county of Jackson and State of Missouri, have invented certain new and useful Improvements in Balanced Rotary Valves; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to a rotary valve for explosive engines, and has for its principal object to provide a rotary valve wherein the impact occasioned by explosion of gas within an engine cylinder is balanced to obviate uneven pressure and strain on the valve and its inclosing parts. In accomplishing this object I have provided improved details of structure, the preferred embodiment of which is illustrated in the accompanying drawings, wherein:

Figure I is a perspective view of an exemplification of an explosive engine in which my improved valve may be used. Fig. II is a longitudinal vertical section of the same. Fig. III is a transverse vertical section on the line III—III, Fig. II. Fig. IV is a detail perspective view of the rotary valve. Fig. V is a perspective view of a retaining collar in the delivery end of the valve housing. Fig. VI is a detail perspective view of the valve balancing cup or thimble.

Referring more in detail to the parts:— 1 designates an explosive engine of an ordinary vertical type and is here shown merely to facilitate the illustration of my improvements, and with the understanding that the valve may be combined in a horizontal engine, vertical engine, or other types of explosive engines.

The engine 1 comprises a cylinder 2, wherein charges of fuel are exploded, and a valve housing 3 containing mechanism for controlling the passage of fuel to the cylinder, the compression and ignition of the charge and exhaustion of the burnt or spent gases at proper intervals.

The specific construction of the housing 3 comprises interior chambers 5 and 6 of different diameter, the large chamber being

at the outer end of the housing and having an annular seat 7 on account of the difference in diameter between the two chambers. Revolvably mounted within the smaller 60 chamber 5 is a rotary valve 9, having a port 11 therein adapted for independent communication with the intake and exhaust ports 12—13, that extend through the housing 3 to the chamber 5 from the respective 65 intake and exhaust conduits 14—15 that are fed from a suitable carburetor and may deliver through a suitable muffler, not shown.

The valve 9 has an integral base 17 that closes its outer end and forms a cup-shaped 70 structure that fits snugly within the chamber 5 to obviate the escape of gas or vapor between the rotating or valve ring and the inner surface of the housing and obviates the necessity for stuffing boxes or packing 75 rings, the base of the cup being spaced from the base of the housing by a neck or bur 18 on the cup base that projects outwardly and engages the cover.

Seated within the valve 9 is a cup 23 having intake and exhaust ports 24—25 adapted for communication with the intake and exhaust ports 12—13 in the valve housing through the valve port 11, when the latter is brought to proper position, and having 80 a balance port 26 opposite the intake and exhaust ports, the intake and exhaust ports 24—25 being preferably arranged longitudinally of the cup 10 and the balance port circumferentially therein in order that the 85 balancing pressure may be extended over a greater circumferential area of the valve, it being apparent that as the intake and exhaust ports are located adjacent each other, the single balancing port may be located di- 95 ametrically opposite the intake and exhaust ports, so that expansion of gases within the cylinder and explosion chamber may not cause unequal pressure or strain on the rotating valve; the cup 23 also protecting the 90 rotating valve 9 from carbon and heat of the explosion.

The open end of the cup 23 has a flared mouth 27 overlying the beveled outer end 28 of the valve ring 9 and is provided with 105 flange 29 which overlies the seat 7 in the valve housing and is preferably separated therefrom by a packing ring 30 to better insure against the leakage of gas through the joint. The cup 23 is held in place by a 110 retaining collar 31, which is preferably formed integral with a cap 32 that may be

attached to the housing by bolts 33 and seals the valve chamber, the sleeve being provided with sockets 34 for receiving the ends of dowel-pins 35 that project from the ring flange 29, the sleeve being provided with a port 36 through which the charges of fuel vapor may be delivered from the outer valve chamber into the interior of the cylinder 2. In order to properly lubricate the valve 23, I provide a port 37 in its base end, which communicates with the housing chamber 19 to allow lubricant to pass from the chamber to the interior of the valve and about the cup 23.

15 A spark plug 38 is located in any suitable position on the engine for performing the usual function in proper sequence relative to the intake and exhaust.

In order to rotate the valve 9 in proper 20 synchronism with the sparking mechanism, I provide a shaft 39, which is revolvably mounted in a bearing boss 40 on the end of the housing and is fixed at its inner end in the hub 18 of the valve ring 9; the outer end 25 of the shaft being provided with a drive wheel 41 whereby the shaft may be driven from suitable mechanism that may be actuated from the crank shaft of the engine that is served by the valve.

30 In assembling the parts, the rotary valve may be first installed by removing the drive wheel and forcing the valve into the inner chamber of the housing, so that the shaft 39 projects through its bearing. With the 35 valve in place the cup is dropped into the valve chamber with its annular flange resting on the packing ring and the cap, with its collar, is next installed, so that the dowel-pins on the valve cup project into the sockets 40 in the inner end of the collar. With the parts so arranged and operatively connected with the engine driving mechanism, the valve cup is held against rotation, while rotation of the shaft 39 will rotate the valve 45 ring, so that communication is established at proper intervals between the intake and exhaust ports; the operation in this respect being that of any ordinary explosive engine, except as to the method of securing 50 the communications by the rotary member instead of the usual puppet valves.

With a construction of this character, were the cup 23 closed except for the intake and exhaust ports, when a charge would be 55 exploded in the cylinder the explosion of each charge would exert a pressure through the cup ports against the rotary valve ring, which would tend to drive the ring outwardly and thereby exert a retarding contact of the ring on the inner face of the housing, and as the presence of the intake and exhaust ports in alinement with the like ports in the valve cup would afford no backing for the rotary ring at such points, there would be a tendency to force the ring 60

to wear out of shape, particularly after repeated explosions. In order, however, to balance the pressure on the valve ring, I have provided the balance port in the valve cup, so that when each charge is exploded 70 the pressure in the cup is relieved equally on opposite sides of the rotary ring and such uneven retarding pressure is eliminated, the circumferential arrangement of the balance pin extending the impact of the 75 expansion about the valve ring to obviate excessive pressure along any limited longitudinal area.

Having thus described my invention, what I claim as new therein, and desire to 80 secure by Letters-Patent, is:—

1. A valve comprising relatively stationary and movable members, having ports adapted for communication at proper intervals, and one having a separate balancing 85 port, whereby pressure on the other member, due to an exploded charge, is balanced, substantially as set forth.

2. A rotary valve comprising relatively stationary and movable members, having 90 ports adapted for communication at proper intervals, and one having a balancing port extending transversely relative to the first named ports.

3. A rotary valve comprising a housing 95 having separate intake and exhaust ports, a stationary member having separate intake, exhaust and balance ports, and a rotary member interposed between the stationary member and the housing, and having a single port adapted for separate communication with the ports in the stationary member. 100

4. A rotary valve comprising a housing having intake and exhaust ports, a valve 105 member contained within the housing and having intake and exhaust ports adapted for communication with the housing ports, and having an opposite balance port, a sleeve rotatably mounted between said valve 110 member and the inner face of the housing, and having a port adapted for establishing communication between the housing and valve member, and means for rotating said member. 115

5. A rotary valve comprising a housing, closed at one end and having intake and exhaust ports, and having a lubricant port in its closed end, a valve member rotatably mounted within the housing and having a closed end at the closed end of the housing, the closed end of the valve member having a projection spacing the same from the end of the housing and having a lubricant port in its closed end and a valve port in its side 125 wall, a stationary valve member contained within the rotatable member and having intake and exhaust ports adapted for communication with the intake and exhaust ports in the housing. 130

6. A rotary valve comprising a housing, closed at one end and having intake and exhaust ports, a stationary valve member in said housing, spaced from the ends of the housing and having intake and exhaust ports, and a rotary valve member interposed between the stationary member and the housing, and spaced from the ends of the housing, to form an oil cup, the end of said rotary member having a channel leading therethrough from the oil cup, for supplying lubricant to the members, substantially as set forth.

7. A rotary valve comprising a housing having a closed end and having intake and exhaust ports, a valve member fixedly mounted within the housing in spaced relation thereto and having intake and exhaust

ports in alignment with the intake and exhaust ports in the housing, a valve member 20 rotatably mounted between the fixed valve member and the housing and having a closed end, provided with an outwardly projecting hub for spacing the same from the base of the housing to form a chamber, the said rotatable member having a valve port in its side wall and a lubricant port in its closed end and the housing having a lubricant conduit opening to said chamber.

In testimony whereof I affix my signature 30 in presence of two witnesses.

GEO. L. SCHOFIELD.
